UNITED STATES PATENT OFFICE

162,128

LIGHT PROJECTOR

Philip B. Clark, Stroudsburg, Pa., assignor to
McGraw Electric Company, Milwaukee, Wis., a
corporation of Delaware

Application May 31, 1950, Serial No. 10,286

Term of patent 14 years

(Cl. D48—20)

To all whom it may concern:

Be it known that I, Philip B. Clark, a citizen of the United States, residing at Stroudsburg, in the county of Monroe and State of Pennsylvania, have invented a new, original, and ornamental Design for Light Projectors, of which the following is a specification, reference being had to the accompanying drawing, forming a part hereof, in which:

Fig. 1 is a perspective view of a light projector, showing my new design;

Fig. 2 is a side perspective view thereof;

Fig. 3 is an elevational view showing the side opposite Fig. 2; and

Fig. 4 is a top plan view.

The dominant features of my design reside in that portion shown in full lines in the drawing.

I claim:

The ornamental design for a light projector, as shown and described.

PHILIP B. CLARK.
